DRYING APPARATUS

Filed Feb. 12, 1925

Inventor

Edward C. Reader,
Hull, Brock & Heat,

Attorney

UNITED STATES PATENT OFFICE.

EDWARD C. READER, OF CLEVELAND, OHIO.

DRYING APPARATUS.

Application filed February 12, 1925. Serial No. 8,702.

To all whom it may concern:

Be it known that I, EDWARD C. READER, a citizen of the United States, residing at Cleveland, in the county of Cuyahoga and State of Ohio, have invented a certain new and useful Improvement in Drying Apparatus, of which the following is a full, clear, and exact description, reference being had to the accompanying drawings.

10 This invention relates to drying apparatus, and more particularly to apparatus for drying material in a finely divided condition, such as sand. The general object of the invention is to provide an apparatus of 15 this character which will enable the material to be dried quickly and efficiently and without danger of adhering to the walls of the drying conduit through which it is conducted to the place of storage. For convenience 20 of description, the material to be dried will be referred to hereinafter as sand.

Further and more limited objects of the invention will appear hereinafter and will be realized in and through the construction 25 and arrangement of parts shown in the drawings, wherein Fig. 1 represents a sectional side elevation of a drying apparatus embodying my invention; Fig. 2 is a detail in end elevation and Fig. 3 a detail in central sectional elevation of the drying-end of 30 the nozzle through which heated air is discharged into the drying conduit.

Describing the various parts by reference characters, 1 denotes a heating chamber, 35 which may be of any approved construction, the chamber herein being provided with an opening 2 through which a combustible mixture is supplied from a burner 3. The burner in the installation shown herein is a burner 40 of the injector burner type having a supply pipe 4 for oil and a pipe 5 for delivering air under pressure thereto. The burner in its details forms no part of my invention, it being sufficient for my purpose to utilize 45 any one of the existing numerous types of injector burners employing oil or gas and air under pressure.

6 denotes a blower, supported on a suitable stand 7 and having the delivery pipe 8 ex-

tending across the chamber 1 and provided 50 with a tapered or frusto-conical nozzle portion 9 projecting into a correspondingly-shaped opening 10 in the wall of the said chamber. From this opening, a conduit 11 extends to a storage tank 12 for the dried 55 sand, the said tank being shown as provided with a gate-controlled outlet 13 which is adapted to discharge the sand, as desired, upon a conveyor 14.

The conduit 11 is provided with a hopper 60 12, which hopper is adapted to deliver into the conduit through a spout 13. The hopper is provided with a rotary sand-agitating device 14, which is adapted to break up the caked, moist sand, the said device being provided with a pulley 15 by means of which it may be driven, if desired.

16 denotes a conveyor, the upper end of which extends around a sprocket 17 and which is provided with buckets, some of 70 which are shown at 18 and which are adapted to deliver the wet or moist sand into the hopper.

The delivery end of the air conduit 8 and the nozzle are completed by an additional 75 tapered or frusto-conical sleeve 19, which is fitted over the end of the nozzle part 9, the sleeve being provided with spiral blades 20 cast with, or otherwise secured at their outer ends to the inner wall of the sleeve, the inner ends of the blades projecting from a central forwardly-flaring conical hub 21 having its apex extending inwardly or rearwardly.

With the parts constructed and arranged 85 as described, the chamber 1 will be heated by the burner 3, the air for the burner being preferably taken from the conduit 8 by the pipe connection 5, said connection being provided with a valve 5^a. The blower being 90 driven from any suitable source of power, the air will operate to atomize the oil or other liquid fuel and deliver the mixture into the chamber 1, in the manner usual with injector burners, and the mixture will be burned in 95 said chamber, the products being delivered into the conduit 11. Air heated by the products of combustion in the chamber 1, will be

forced through the conduit 8 and, by reason of the construction of the nozzle 9, 19-21 will be thrown outwardly, with a whirling motion into the conduit 11. The sand to be dried will be delivered into this stream of air and products of combustion entrained by the action of the nozzle, will be thoroughly dried by the hot air and the products of combustion, and will be delivered by the 10 blast into the tank 12.

It will be noted that the conduit 11 is of considerably greater cross-sectional area than is the conduit 8. This provides a relatively large area for the expansion of the 15 blast of air and combustion gases and for the whirling of the sand thereby, and enables the particles of wet sand to be separated and thoroughly dried, without adherence to the wall of the conduit 11.

20 The conduit 8 is provided with a sliding gate 8^a by means of which the air blast therethrough may be regulated or shut off, as desired.

The apparatus shown herein has proven 25 efficient in action, not only in preventing the caking of the sand and its adherence to the wall of the conduit 11, but also in effecting the complete and rapid drying of the sand.

Having thus described my invention, what 30 I claim is:—

1. An apparatus of the character described comprising in combination a heating chamber, a conduit extending from said chamber, means for delivering material to be dried into said conduit, a conduit in the said chamber and having its delivery end aligned with the adjacent end of the first-mentioned conduit, means for forcing a drying fluid through the second conduit, and 35 means for imparting a whirling motion to the fluid delivered from the second conduit into the first conduit and for throwing such fluid outwardly against the inner wall of such second conduit.

45 2. An apparatus of the character described comprising in combination a heating chamber, a conduit extending from one side of said chamber, means for delivering material to be dried into said conduit, a conduit extending across the said chamber and having its delivery end aligned with the adjacent end of the first mentioned conduit, with an annular space between such ends, means for forcing a drying fluid through the second conduit, and means for imparting a 50 whirling motion to the fluid delivered from the second conduit into the first conduit and for throwing such fluid outwardly against the inner wall of such second conduit.

60 3. An apparatus of the character described comprising in combination a heating chamber, a conduit extending from said chamber and communicating therewith, means for delivering material to be dried 65 into said conduit, a conduit in the said chamber and having a frusto-conical delivery end arranged within and spaced from the frusto-conical inlet of the first conduit, means for forcing a drying fluid through the second conduit, and means for imparting a whirling motion to the fluid delivered therefrom into the first conduit and for throwing such fluid outwardly against the inner wall of such second conduit.

70 4. An apparatus of the character described comprising in combination a heating chamber, a conduit extending from said chamber and communicating therewith, means for delivering material to be dried into said conduit, a conduit in the said chamber and having a delivery end arranged within the inlet of the first conduit, the said delivery end of the second conduit being provided with a central conical hub and with spiral blades located between said hub and the inner wall of such delivery end whereby a heated drying fluid passing through the second conduit is given an outward whirling motion causing it to press against the inner wall of the second conduit.

75 5. In an apparatus of the character described comprising in combination a heating chamber, a conduit extending from one side of said chamber and communicating therewith, means for delivering material to be dried into said conduit, a conduit in the said chamber and having a delivery end arranged within the inlet of the first conduit, the said delivery end of the second conduit being provided with a central hub and with spiral 80 blades extending from said hub toward the inner wall of such delivery end whereby a heated drying fluid passing through the second conduit is given an outward whirling motion causing it to press against the inner wall of the second conduit.

85 6. In an apparatus of the character described, the combination of a heating chamber, a conduit communicating therewith and extending therefrom, means for delivering into said conduit particles to be dried, a conduit in the said chamber and having its delivery end aligned with the receiving end of the first mentioned conduit, the cross sectional area of the first conduit being materially greater than that of the second conduit, and means for supplying a drying fluid through the second conduit and for delivering the same in an outwardly-whirling motion direction into the first conduit.

90 7. In an apparatus of the character described, the combination of a heating chamber, a conduit communicating with and extending therefrom, means for feeding particles to be dried into said conduit, a conduit in the said chamber and adapted to deliver into the first conduit, means for supplying air under pressure through the second conduit, a fluid-pressure burner for heating the said chamber, and a connection 95

100 105 110 115 120 125 130

between the said burner and the second conduit for supplying air under pressure to operate such burner.

8. An apparatus of the character described comprising in combination a heating chamber, a conduit extending from said chamber and communicating therewith, means for delivering material to be dried

into said conduit, a conduit in the said chamber and having a frusto-conical delivery end 10 arranged within and spaced from the inlet of the first conduit, and means for forcing a drying fluid through the second conduit.

In testimony whereof, I hereunto affix my signature.

EDWARD C. READER.
